US00D697127S

(12) **United States Design Patent**
O'Donnell et al.

(10) **Patent No.:** US D697,127 S
(45) **Date of Patent:** ** Jan. 7, 2014

(54) **CAMERA MOUNT**

(71) Applicant: **Contour, Inc.**, Seattle, WA (US)

(72) Inventors: **Laura O'Donnell**, Hermosa Beach, CA (US); **Carm Pierce**, Stanwood, WA (US); **Carl Perkins**, Seattle, WA (US)

(73) Assignee: **Contour, Inc.**, Seattle, WA (US)

(**) Term: **14 Years**

(21) Appl. No.: **29/439,575**

(22) Filed: **Dec. 12, 2012**

Related U.S. Application Data

(62) Division of application No. 29/422,605, filed on May 22, 2012, now Pat. No. Des. 675,242, which is a division of application No. 29/368,734, filed on Aug. 27, 2010, now Pat. No. Des. 663,350.

(57) **CLAIM**

The ornamental design for a camera mount, as shown and described.

DESCRIPTION

FIG. 1 is a top, front, and right side perspective view camera mount, showing our new design;

FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a bottom view thereof.

The broken lines showing in FIGS. 1-7 depict environmental features and form no part of the claimed design.
